UNITED STATES PATENT OFFICE.

JOSEPH H. DODSON, OF KANKAKEE, ILLINOIS.

DESIGN FOR A ROCKER.

58,555.

Specification for Design.

Patented Aug. 2, 1921.

Application filed December 11, 1920. Serial No. 430,062. Term of patent 14 years.

To all whom it may concern:

Be it known that I, JOSEPH H. DODSON, a citizen of the United States, residing at Kankakee, in the county of Kankakee and State of Illinois, have invented a new, original, and ornamental Design for a Rocker, of which the following is the specification, reference being had to the accompanying drawing, forming part thereof.

The figure is a perspective view of a rocker, showing my new design.

I claim:

The ornamental design for a rocker, as shown.

JOSEPH H. DODSON.
